UNITED STATES PATENT OFFICE.

JOSEPH KAHN, OF CHICAGO, ILLINOIS.

LOOSE-LEAF BINDER.

Application filed December 4, 1920. Serial No. 423,182.

To all whom it may concern:

Be it known that I, JOSEPH KAHN, a citizen of the United States, and a resident of the city of Chicago, in the county of Cook 5 and State of Illinois, have invented certain new and useful Improvements in a Loose-Leaf Binder; and I do hereby declare that the following is a full, clear, and exact description of the same, reference being had 10 to the accompanying drawings, and to the numerals of reference marked thereon, which form a part of this specification.

This invention relates more particularly to an improved type of a loose leaf binder 15 wherein longitudinally adjustable posts are adapted to be removably locked to a binder cover by locking members movably mounted on the binder cover.

It is an object of this invention to provide 20 a binder wherein a binding post having an apertured end is adapted to be locked in position by means of a locking member adjustably mounted on a binder cover.

It is also an object of the invention to 25 provide a binder wherein a back has hinged- ily connected thereto side members to which covers are hingedly attached, said covers carrying locking members thereon adapted to removably engage the ends of adjustable 30 loose leaf posts.

Another object of the invention is the construction of a loose leaf binder the covers of which are adapted for carrying locking members for retaining binder posts in position.

It is an important object of this invention to provide an improved loose leaf binder of simple and effective construction wherein posts are adapted to be pivotally connected to the binder covers for holding loose leaves in place.

Other and further important objects of this invention will be apparent from the disclosures in the specification and drawings.

The invention (in a preferred form) is 45 illustrated in the drawings and hereinafter more fully described.

On the drawings:

Figure 1 is a top plan view of an improved 50 binder in open position showing parts of the covers broken away with the flaps turned up to disclose the locking members.

Figure 2 is an enlarged fragmentary detail section taken on line 2-2 of Figure 1 55 with parts in elevation.

Figure 3 is an enlarged detail section of

one of the binding posts taken on line 3-3 of Figure 2.

Figure 4 is a fragmentary detail section taken on line 4-4 of Figure 1. 60

Figure 5 is a detail section taken on line 5-5 of Figure 1.

Figure 6 is a detail section taken on line 6-6 of Figure 1.

Figure 7 is a top plan view of an open 65 binder partly broken away to show a modified form of locking device.

Figure 8 is a top plan view of another open binder partly broken away and disclosing another modified form of construc- 70

Figure 9 is an enlarged fragmentary section taken on line 9-9 of Figure 8.

Figure 10 is a similar section showing the 75 covers in closed position.

As shown on the drawings: The reference numeral 1 indicates a binder back having hingedly connected to the sides thereof side sections 2 and 3 which together with said back form the rear portion 80 of the binder. Hinged to the front margins of the side sections 2 and 3 are covers 4. The hinges connecting the side sections with the back 1 and covers 4 may be formed by the binder covering which forms the exterior finish for the binder. A flexible flap 5 is provided on the inner surface of each binder cover 4.

Each binder cover 4 has rigidly secured and seated in the inner face thereof a metal 90 strip or plate 6, the ends of which are bent to form lugs or grips 7 which project into the cover as shown in Figure 5. Each plate 6 has integrally formed on the inner longitudinal margin thereof a plurality of pairs 95 of projecting spaced eyes 8. Pivotally mounted on each plate 6 are a plurality of locking hooks 9, one for co-operation with each pair of eyes 8. The cover flaps 5 are adapted to normally cover the plates 6 and 100 the locking hooks 9 mounted thereon. The various pairs of eyes on each cover plate 6 are positioned opposite the eyes on the other cover plate as illustrated in Figure 1.

For the purpose of removably holding a 105 plurality of perforated loose leaves 10 in place adjustable binding or impaling posts are provided. Each post comprises two semi-cylindrical post sections 11 and 12 positioned with the flat faces adjacent one 110 another. A circular flange or head 13 is integrally formed on the outer end of each

post section and has an apertured lug or eye 14 integrally formed diametrically on the outer face thereof as shown in Figure 3. Each post section 11 is provided with a 5 longitudinal row of internally threaded holes or openings 15 for the purpose of removably receiving the threaded ends of retaining screws 16, a plurality of which are carried by each post section 12. The screw holes in 10 each post section 12 are countersunk to receive the heads of the screws 16 seated therein. By removing the screws 16 the length of a binding post may be varied to suit requirements. One end of a binding post is 15 locked to a binder cover by engaging the eye 14 between two of the binder plate eyes 8 and then projecting a hook 9 through the registering openings of said eyes. The leaves 10 may then be engaged on the post, 20 after which the other end of the post is locked to the other binder cover by engaging a hook 9 through the eyes 8 and 14. It will thus be noted that loose leaves 10 may be easily and conveniently engaged on either or 25 both ends of a binding post by simply opening the binder and disengaging the hooks 9 from the eyes 8 and 14.

Figure 7 discloses a modified form of an 30 improved type of binder wherein the covers and binding posts are constructed similar to those illustrated in Figure 1. In this case, however, the cover plates 6 are replaced by cover plates 17. Slidably engaged on each plate 17 is a locking member 35 comprising a bar or plate 18 knurled at 19 and having longitudinal slots 20 therein. Arms 21 are integrally formed at right angles on both ends of the locking plate 18 and each of said arms has a locking pin or 40 lug 22 integrally formed thereon at right angles. The locking pins are both directed in the same direction and are adapted to be removably engaged in the eyes 14 of the binding posts to hold loose leaves in place. 45 Set screws 23 project through the locking plate slots 20 and engage in the cover plates 17 to guide and limit the movement of the locking plates.

The operation of the modified form of 50 device shown in Figure 7 appears self-evident. In this case operation of a locking plate 18 acts to either lock or unlock a plurality of binding posts with one operation to permit loose leaves to be secured in place 55 or removed from the binder as the case may be. It will of course be understood that if desired one piece binding posts having integral end eyes may be used in place of the adjustable binding posts shown and described. 60

Figures 8 to 10 inclusive illustrate another modified form of a binder wherein only one end of the binding posts are adapted to be removably locked to a binder cover, the

other ends of the binding posts being rigidly 65 secured in place.

In this case the binder comprises a back 24 having hinged to the sides thereof side sections 25 and 26. The side section 26 is wider than the side section 25 and has 70 hingedly connected thereto a binder cover 27. Rigidly secured at right angles on the inner face of the wide side section 26 are a plurality of binding posts 28, on the free 75 ends of which are integrally formed apertured lugs or eyes 29. Loose leaves 30 are adapted to be engaged on the binding posts 28.

Hinged to the narrow side section 25 is a 80 binder cover 31 of a width greater than the width of the cover 27 to compensate for the difference in widths of the side sections 25 and 26. A metal strip or plate 32 is secured in the inner face of the cover 31 adjacent the hinged margin, and pivotally 85 mounted on said plate are a plurality of locking hooks 33. Eyes 34 are integrally formed on the inner edge of the plate 32 and are arranged in pairs to receive the eyes 29 of the binding posts therebetween to 90 permit the locking hooks 33 to lockingly engage through the registering openings of said eyes to lock the binding posts to the cover 31.

I am aware that numerous details of construction may be varied through a wide range without departing from the principles of this invention, and I therefore do not purpose limiting the patent granted otherwise than necessitated by the scope of the 95 appended claims.

I claim as my invention:

1. A loose leaf binder comprising a back section, covers hinged thereto, plates secured on said covers, eyes formed on said plates, binding posts, eyes formed thereon adapted to be engaged between the eyes on said plates, and hooks pivotally mounted on said plates adapted to be engaged through said plate eyes and said binding post eyes 100 to hold the binding posts locked in position.

2. The combination with a pair of binder covers, of binding posts connecting the same and each comprising a pair of interfitting sections, heads formed at right angles on 115 said sections, eyes formed on said heads, one of said sections having threaded openings therein, and screws on the other section adapted to be threaded into said openings to removably hold the sections locked in an 120 adjusted position.

In testimony whereof I have hereunto subscribed my name in the presence of two subscribing witnesses.

JOSEPH KAHN.
